SEGMENT BUFF WITH INCLINED SEGMENTS
William J. Miller, Conever, N.C., assignor to Jackson
Buff Corporation, a corporation of North Carolina

Filed Jan. 22, 1962, Ser. No. 167,858

2 Claims. (Cl. 51—173.5)

The present invention is directed to a buffing wheel, and more particularly to a buffing wheel having relatively stiff, finger-like buffing segments that extend outwardly at an inclination with respect to a radial position, with all segments inclined in the same direction, the finger-like buffing segments thereby being presented to an article being buffed at a trailing inclination when the buffing wheel is rotated in the direction opposite to the direction of inclination.

Buffing wheels having finger-like buffing segments extending radially outwardly are used effectively in buffing contoured surfaces as the segments are substantially individually flexed as they pass across the surface being buffed and thus each segment will generally follow the contour of the surface substantially independently of the flexure of the adjacent segments.

To obtain satisfactory buffing action the individual finger-like buffing segments should be relatively stiff so that they will enter and effectively buff recesses in the surface being buffed. However, due to the radial positioning of the buffing segments, the surface being buffed applies a force to the finger-like segments in a direction normal to their lengths which is the direction of force causing the greatest flexing of the segments. In addition the finger-like construction renders the segments particularly susceptible to flexure by a force in this normal direction.

By the present invention a buffing wheel with finger-like buffing segments is provided, having the advantages of prior buffing wheels of this type, and in addition providing increased resistance to flexing of the individual segments with an accompanying increase in buffing effectiveness, particularly for contoured surfaces.

This advantage is obtained by a buff construction wherein each finger-like segment is inclined from a radial position in a direction opposite to the direction of rotation of the buffing wheel so that the force tending to flex the segments, which force is generally tangential to the buff, is inclined with respect to the inclined finger-like segments, and thus the flexing component of the force is reduced in accordance with the degree of inclination.

A further advantage of this inclined construction is that a more dense and compact buffing wheel can be constructed as the inclination increases the circumferential extent of each segment at the periphery of the buff. Further compacting can be readily produced with the buff of the present invention by arranging the segments in overlapping relation. With the increased peripheral extent of the inclined segments, this overlapping of the segments can easily extend the full length of the segments, thereby eliminating cavities in the surface of the buff between segments. The elimination of cavities results in a corresponding elimination of streaking and uneven cutting of the surface being buffed.

Additional compactness and stiffness may be obtained by a particular overlapping of the segments wherein each segment overlaps one of the adjacent segments and is similarly overlapped by the other adjacent segment. This results in the segments being inclined with respect to a radial plane so that when a number of circular sections, each having these overlapping segments thereon, are combined in side-by-side relation to form a composite buffing wheel the inclined segments of each section will extend into the planes of the adjacent sections and will

2

interlock with the similarly inclined segments of the adjacent sections, providing a substantially solid mass of buffing material on the surface of the buff without cavities between sections.

5 Other and further advantages and features of the present invention will be apparent from the following description and drawings in which:

FIG. 1 is a side elevational view, partially broken away, of a buffing wheel section incorporating the preferred embodiment of the present invention;

10 FIG. 2 is a top plan view of the buffing wheel section of FIG. 1;

15 FIG. 3 is a view similar to FIG. 2 and showing the positions of a number of sections combined in a multi-section buffing wheel;

FIG. 4 is a top plan view of a strip of folded buffing material used to make the finger-like buffing segments of the buffing wheel section of FIG. 1; and

20 FIG. 5 is an enlarged view of a portion of the buffing wheel section illustration of FIG. 1.

In the embodiment illustrated in the drawings a single buffing wheel or section 10 is constructed with a plurality of relatively narrow finger-like buffing segments 12 mounted in and extending outwardly from an annular lacing 14. The finger-like segments 12 are secured together adjacent the lacing 14 by circular stitching 16. Outwardly of the stitching 16 the segments 12 are free of securing and capable of independent relative flexing. Additional rows of stitching may be utilized to provide increased stiffness, if desired.

The finger-like buffing segments 12 of the embodiment illustrated are formed from a sheet of buffing material, such as cotton, sisal or other types of material, and may be formed conventionally with bias cut edges. The sheet 35 is folded upon itself a number of times to form a relatively narrow strip 18 as illustrated in FIG. 4. The plies of this multi-ply folded strip 18 may then be secured together by longitudinal stitching 20, which not only holds the plies together but imparts a stiffness that increases the resistance to flexing in a direction normal to the length of the strip. The number of rows of stitching 20 may vary from none to six or more depending on the width of the segments and the desired stiffness.

40 To form the finger-like segments 12 and the strip is 45 cut transversely at spaced distances corresponding to the desired length of the segment. As seen in FIG. 4 the strip is cut at a slight inclination, such as at 5°, to the transverse direction so that the ends 22 of the lengths 12 are inclined slightly with respect to a direction normal to the segments so that when the segments 12 are 50 mounted on the lacing 14 with their inner ends 26 tangentially positioned on the lacing 14 the segments 12 will extend in a direction inclined slightly from a radial position and the side edges 24 of the segments will be 55 similarly inclined. The angle at which the strip 18 is cut may be varied to provide desired results. Satisfactory results may be obtained using angles in the range of 5°—10°, but it is not intended that the present invention be limited to this range.

60 As best seen in FIG. 5 the inner end 26 of each segment 12 is positioned tangentially against the base 28 of the lacing 14 and is secured in place by the gripping teeth 30 of the lacing with all of the elements 12 similarly placed for inclination of all the segments in the same direction. The direction of inclination is opposite to the intended direction of rotation of the buffing wheel section 10 so that the segments will strike the surface being buffed at a trailing inclination and the force of the surface being buffed against the segments will be inclined with respect to a normal direction, thereby reducing the effective bending force exerted against the segments 12 and reducing

the amount of flexure of the segments for enhanced buffing action.

As the outer ends 32 of the segments 12 are cut at the same inclination as the inner ends 26 a saw tooth periphery is formed on the buffing wheel sections 10 as indicated in dotted lines in FIG. 5. If desired, the periphery of the buff may be trimmed to provide a smooth circular surface.

The finger-like buffing segments 12 are arranged serially around the lacing 14 in overlapping relation to each other. Each segment, such as the one indicated as 34, overlaps one of the adjacent segments 36 and is itself similarly overlapped by the other adjacent segment 38 with the result that the segments 12 are inclined slightly from the radial plane of the buffing wheel section 10. Due to the previously described inclination of the segments 12 from radial positions and the amount of overlap the segments are in overlapping relation throughout their entire lengths. This provides a solid periphery without any spaces or cavities between the segments, as seen in FIGS. 2 and 3.

The buffing wheel section 10 may be used by itself, but normally a plurality of identical sections are mounted side by side to form a composite buffing wheel 40, such as that shown in FIG. 3. The inclination of the segments 12 from the planes of the sections is of particular significance when using the sections in a composite buffing wheel, in which case the inclination results in the segments extending into the planes of the adjacent sections and interlocking with the corresponding segments of these other sections to form a dense compact mass of buffing material without any cavities between sections.

A typical example of a buff made in accordance with the present invention, but not intended as a limitation to the present invention, is a buff of the type illustrated having an outer diameter of 17 inches using an annular lacing of 7 inch inner diameter. The finger-like segments are each $1\frac{1}{8}$ inches wide and $5\frac{1}{8}$ inches long. The segments are cut at a 7° angle and when mounted on the lacing extend at an angle of approximately 15° from a radial position, with all segments extending in the same direction.

The present invention has been described above for purposes of illustration only, and is not intended to be limited by this description or otherwise except as defined in the appended claims.

I claim:

1. A buffing wheel comprising a plurality of contiguous

5 circular buff sections aligned axially, each buff section having an annular supporting member and a plurality of relatively stiff, individually flexible, finger-like buffing segments secured to and extending outwardly from said supporting member, said buffing segments being arranged serially about the periphery of the annular supporting member with each buffing segment partially overlapping one adjacent segment and being partially overlapped by the other adjacent segment to position each segment at an inclination to the plane of its buff section and to extend into the plane of adjacent buff sections in interlocking engagement with the inclined segments of said adjacent buff sections, said buffing segments being formed from a strip of longitudinally multi-folded buffing material cut transversely in buffing segment lengths at an inclination to a line perpendicular to the length of the strip, one of the cut inclined edges of each buffing segment being positioned tangentially on the periphery of the supporting member to dispose each of said finger-like buffing segments at an inclination from a radial position with all segments inclined in the same direction to present the finger-like segments to an article being buffed at a trailing inclination when the buff is rotated in the direction opposite the direction of radial inclination.

2. A buffing wheel comprising an annular supporting member, a plurality of relatively stiff finger-like buffing segments secured to and extending outwardly from said supporting member, each of said finger-like buffing segments having an inner end tangentially positioned on the periphery of the supporting member and parallel side edges extending outwardly from the inner edge at an inclination to a direction normal to the inner edge, thereby inclining each of said buffing segments from a radial position, with all segments being inclined in the same direction to present the finger-like segments to an article being buffed at a trailing inclination when the buff is rotated in the direction opposite to the direction of inclination, said buffing segments being formed from a strip of multi-folded buffing material cut transversely in buffing segment lengths and at an inclination to a line perpendicular to the side of the strips.
